DESIGN FOR A GAME BOARD

Bennett L. Petersen, St. Paul, and Douglas J. Hafften, Minneapolis, Minn.

Application March 8, 1939, Serial No. 83,440

Term of patent 14 years

To all whom it may concern:

Be it known that we, Bennett L. Petersen and Douglas J. Hafften, citizens of the United States, the former residing at St. Paul, in the county of Ramsey and State of Minnesota, and the latter residing at Minneapolis, in the county of Hennepin and State of Minnesota, have invented a new, original, and ornamental Design for Game Boards, of which the following is a specification, reference being had to the accompanying drawing, forming part thereof.

Fig. 1 is a top plan view of a game board showing our new design;

Fig. 2 is a bottom plan view of the game board;
Fig. 3 is a side elevational view of the game board; and

Fig. 4 is an end elevational view of the game board.

We claim:

The ornamental design for a game board, as shown.

BENNETT L. PETERSEN.
DOUGLAS J. HAFTEN.
